O. BALLARD

PNEUMATIC PIANO CONTROL

Filed Feb. 23, 1926

UNITED STATES PATENT OFFICE.

OTIS BALLARD, OF TOLEDO, OHIO.

PNEUMATIC PIANO CONTROL.

Application filed February 23, 1926. Serial No. 89,945.

This invention relates to pneumatically controlled player pianos.

This invention has utility when incorporated in a pneumatically controlled player piano for rendering such instrument capable of playing from reproducing types of player piano records.

Referring to the drawings:

Fig. 1 is a front view of a player piano, parts being broken away;

Fig. 2 is a plan view of the device of the invention herein, parts being broken away;

Fig. 3 is a side view of the device of the invention herein, and

Fig. 4 is a view similar to Fig. 2, on a reduced scale, with the parts in shifted position.

Piano 1 has keys 2 for manual playing. However, it may be desired to reproduce music from a record, and then pedals 3 may operate section pumps 4 for exhausting storage chambers 5, to create a suction or vacuum therein.

Main control duct 6 extends from one of said storage chambers to pneumatic stacks 7 from which branch auxiliary control ducts 8 extending to tracker board 9 having openings 10 therein. Such tracker board extends across spool box 11. The tempo or speed of the piano is controlled by handle 12 and is displayed in the spool box by indicator 13.

Each key on the piano, say eighty-eight in number, is controlled by a separate action or notation motive element from the tracker board from which extends an auxiliary control line 8 to a hammer operating bellows 14 of its action, having communication with the stacks 7. When the player is of the suction type, and the pumps 4 are in operation, there is an intake of air through the openings in the tracker board, causing the corresponding bellows to be exhausted and by collapsing produce a note on the piano through the hammer operating action. There is an opening in the tracker board for rendering effective the action of the note corresponding to each key 2.

When a record is inserted in the spool box and is driven to pass over the tracker board, each perforation in such record will move into registry with a corresponding opening in the tracker board and thus cause the note for such opening to be played.

Due to the rarity of use of the extreme high and low notes of the piano, the tracker board openings therefor in reproducing

pianos are allotted for operating expression devices for speed and sound volume. Special records operate these devices through the medium of such range of the tracker board. When these special records are played upon player pianos which are not equipped with expression devices in such regions, the extreme high and low notes are played out of harmony with the reproduced music, due to the perforations of the record passing over the extreme note control openings. The invention herein avoids such objectionable operation and allows reproducing records to be played as to its notation independently of note interference on player pianos which are not equipped with the special expression devices as devices in the tracker board range. A record controlled piano having only notation motive elements and not equipped with the expression devices is known to the trade as a player-piano as distinguished from a reproducing piano which is a record controlled piano having record controlled expression devices.

The spool box 11 is mounted on bracket 15 extending across the interior of the piano. Spaced from the spool box on the bracket 15 and on the opposite side thereof is member 16 fixedly mounted on the under side of the bracket 15 by screws 17. The member 16 has openings 18 therethrough, herein shown as ten, divided in two sets of five each. In each of the openings 18 there is pressed, metallic elbow ducts 19 to which ducts 20 and ducts 21 extend from the terminal openings in the tracker board. The ducts 20 extend one to each of the left five of the openings at the left terminal of the tracker board, while the ducts 21 extend respectively to the five openings at the right terminal of the tracker board, as looking into the piano from the front.

Screws 22 in said member 18 have washers 23 and 24 thereon with helical springs 25 therebetween to hold a second member 26 yieldably against the member 16. Packing 27 may be glued to the member 16 to form an air tight joint between these members 16, 26. The member 26 is similar to the member 16 and has openings 28 therethrough registering with the openings 18. The openings 28 are ten in number divided into two sets of five each. Metallic elbow ducts 29 are pressed into the openings 28 which register with the openings 18 having the metallic elbow ducts 19 therein. These five

elbow ducts 29 each has an auxiliary duct 30 extending to a hammer action control bellows 14 for the lowest five notes on the piano. The other set of openings 28 to the right of the member 26 each has a metallic elbow duct 31 pressed in the openings 28 which register with the openings 18 equipped with elbow ducts 21 therein. These metallic elbow ducts 31 have lines 32 extending therefrom to the hammer operating bellows 14 for the highest five notes on the piano.

It will thus be seen that the auxiliary control ducts for the extreme notes of the piano pass through this member 16 and the member 26 which is relatively shifted to form a multi-port valve device. The member 26 has slots 33 therein through which the screws 22 pass. This allows the member 26 to be shifted as to the member 16 thereby throwing the ducts 28 out of registry with the ducts 18 so that these auxiliary air ducts are rendered inoperative.

The member 26 has extension 34 from which extends rod 35 to crank 36 keyed to shaft 37 extending into the spool box 11 where it has handle 38 keyed thereon.

When the operator is desirous of playing a record which has been perforated to operate expression devices and the piano upon which it is to be played is not equipped with such expression devices, handle 38 may be switched to "off" position, thereby rendering control lines for the extreme notes inoperative and the record may be played without the annoyance of interference from any playing of the extreme notes. By switching the handle to the "on" position, the operator has full range of the piano. As the extreme five notes are rarely, if ever, used in the making of records, there is no material loss of music due to the cutting off of these ducts.

What is claimed and it is desired to secure by United States Letters Patent is:—

1. A player-piano having a spool-box, a tracker-board in said spool-box having a single line of apertures therein, notation motive elements controlled through a portion of said apertures, expression controlling elements controlled through the remaining portion of said apertures, duct communication means from the notation portion of said tracker-board apertures extending directly to said notation motive elements, duct communication means from said expression controlling tracker-board apertures, a member remote from said track-

er-board and provided with ports to which said duct communication means extend, a second member provided with ports and co-acting with said first member, and duct communication means from the ports of said second member extending to said expression controlling elements, said members being shiftable one as to the other for bringing said ports into and out of registry. 60

2. A player-piano having a spool-box, a tracker-board in said spool-box having a single line of apertures therein, notation motive elements controlled through a portion of said apertures, expression controlling elements controlled through the remaining portion of said apertures, ducts from the notation controlling portion of said tracker-board apertures extending directly to said notation motive elements, a valve remote 70 from said tracker-board comprising a pair of relatively movable members, each provided with ports, ducts extending from the expression controlling element apertures to one of the ports of said members, ducts extending from the ports of the other of said members to said expression controlling elements, and means in said spool-box for shifting one of said members as to the other for throwing the ports out of registry and thereby rendering said expression controlling ducts inoperative. 75

3. A player-piano having a spool-box, a tracker-board in said spool-box having a single line of apertures therein, notation motive elements controlled through a portion of said apertures, expression controlling elements controlled through the remaining portion of said apertures, ducts from the notation controlling apertures extending directly to said notation motive elements, a fixed bar remote from said spool-box having a series of ports therethrough, ducts extending from the expression controlling element apertures to said bar, a second bar adjacent 90 the first bar having a series of ports therethrough normally registering with the first bar ports, ducts as continuations of the ports in said second bar extending to the expression controlling elements, and means extending from said second bar to the spool-box for shifting said second bar as to the first bar for throwing the ports of the two bars into and out of registry. 95

In witness whereof I affix my signature,

OTIS BALLARD.

CERTIFICATE OF CORRECTION.

Patent No. 1,661,318.

Granted March 6, 1928, to

OTIS BALLARD.

It is hereby certified that error appears in the printed specification of the above numbered patent requiring correction as follows: Page 2, line 79, claim 2, strike out the words "one of" and insert the same to follow after the word "of" in line 80; and that the said Letters Patent should be read with this correction therein that the same may conform to the record of the case in the Patent Office.

Signed and sealed this 3rd day of April, A. D. 1928.

Seal.
